UNITED STATES PATENT OFFICE.

THOMAS NATHAN RUSSELL, OF CHICAGO, ILLINOIS, ASSIGNOR TO CHICAGO-CLEVELAND
CAR ROOFING CO., OF CHICAGO, ILLINOIS, A CORPORATION OF ILLINOIS.

CAR-ROOF.

1,203,273

Specification of Letters Patent. Patented Oct. 31, 1916.

Application filed June 26, 1915. Serial No. 36,534.

To all whom it may concern:

Be it known that I, THOMAS NATHAN RUSSELL, a citizen of the United States, residing in Chicago, in the county of Cook and State 5 of Illinois, have invented a new and useful Improvement in Car-Roofs, of which the following is a specification.

The invention relates to outside metal car roofs, and more particularly to the means 10 for securing the roof sheets at the eaves and for finishing the eaves of the roof, and for uniting the side edges of the roof sheets, also to the means for uniting the ridge edges of the roof sheets, all of said securing means 15 leaving the roof sheets free for slight play or movement in all directions and from all edges.

It also relates to improved forms of seam 20 clips, both for the eaves ends of the seam caps and also for the ends of the ridge cap.

In order to make the invention more clearly understood there are shown in the accompanying drawings means for carrying the same into practical effect, without limiting my improvements, in their useful applications, to the particular construction which, for the purpose of example, has been delineated.

In said drawings—Figure 1 is a plan 30 view, partly broken away, of a portion of a car roof embodying the invention. Fig. 2 is a side elevation of a portion of the same, the saddles being broken away to show the caps. Fig. 3 is a transverse vertical section 35 on line III—III of Fig. 1. Fig. 4 is a transverse vertical section of the ridge portion of the roof on line IV—IV of Fig. 1. Fig. 5 is a longitudinal vertical section of the roof and frame at one end of the car, on line V—V of Fig. 1. Fig. 6 is a perspective 40 view of one of the roof sheets. Fig. 7 is a vertical sectional view, on a plane longitudinal of the car, showing two roof sheets, partly broken away, and the seam cap. Fig. 45 8 is a side view of the seam cap, the middle portion being broken away, and before the end flap of the cap has been bent down. Fig. 9 is a plan view of one of the ridge cap sections, partly broken away. Fig. 10 is a 50 side view of the same. Fig. 11 is an end view of the same. Fig. 12 is a perspective view of a portion of one of the eaves hook strips. Fig. 13 is a side view of one of the seam cap clips. Fig. 14 is an outer end view

of the same. Fig. 15 is a section on line 55 XV—XV of Fig. 13. Figs. 16 and 17 are side and end views of the ridge cap clip. Fig. 18 is a transverse vertical sectional view, on a larger scale, of the eaves portion of the roof.

Referring to the drawings, the upper part 60 of the car body frame, which is the supporting frame of the roof, comprises side plates 1, which are united at the ends of the car by end plates 2 of any suitable character. The 65 side and end plates are supported from the sills of the car by suitable framing, not shown.

3 is the side sheathing and 4 the end sheathing.

5 indicates the carlines which extend from side plate to side plate, carrying the ridge pole 6 and purlins 7.

8 is the top sheathing carried by the side plates, purlins and ridge pole, and it ex- 75 tends only to the outer face of the side plates.

At the eaves of the car the side sheathing is overlaid by a side fascia 9 the upper edge of which preferably terminates below the 80 top of the top sheathing.

10 is the end fascia (Fig. 5).

Each roof sheet 11, excepting the end roof sheets, is formed with an integral flange at each side and end. At the ridge end it is 85 formed with an upturned and downturned U-flange 12 which is arranged to interlock with a similar flange on the corresponding sheet which lies at the other side of the ridge. At the eaves end it is bent downward and inward to form an inturned hook-flange 13, adapted to interlock with an eaves hook strip hereinafter described. At each side it is formed with an upstanding U- 90 flange, comprising an upwardly and inwardly bent member 14 and an outwardly extending member 15, the latter being arranged over the main body of the sheet but having its lower edge spaced therefrom.

The side edges of the roof sheets are mov- 100 ably united, by means of their flanges 14, 15 as indicated in Fig. 7, by a tubular seam cap 16 which incloses the said upstanding flanges of the roof sheets and is formed with upwardly and outwardly bent edge flanges 105 17 which are arranged within the tube and which interlock respectively between the said flanges 14 and 15 of the contiguous

roof sheets (Fig. 7). The seam caps 16 extend from the ridge to the eaves of the car, and at the latter end are or may be open. At the ridge end the seam cap is formed with a bendable flap 18 (Fig. 8). By this construction the eaves cap can be interlocked with the roof sheets as above described and slid upward and inward toward the ridge of the car, and after it is in place the flap 18 is bent down to inclose the ridge ends of the seam flanges 14, 15, as seen in Fig. 4. The outer end portions of the ridge flanges 12 are cut away as shown at 19 (Fig. 6) to allow of play and to receive the flap 18, and also to leave space for the securing bolts 20 (Fig. 5) which pass up through the ridge pole.

The ridge seam is finished by ridge cap sections (Figs. 9 to 11) each of which is formed with longitudinal upward U-bends 21 to receive the roof sheet flanges 12, with transverse upward wider U-bends 22 to receive the seam caps 16 and which intersect the bends 21 near one end of the latter, with downwardly inclined flange portions 23 which rest on the roof sheets, with upstanding flanges 24 at the ends of the parts 23 remote from the said bends 22, and with a perforation 25 to permit the passage of the said bolt 20. The flanges 23 which are formed with said upturned end flanges 24 are long enough to extend substantially up to the side of the next seam cap, while the corresponding flanges 23 at the other side 35 of the bend 22 are only sufficiently long to lap a little under the next ridge cap section. By this construction the flanges 24 are included with the seam cap within the U-bend 22 of the next ridge cap section, 40 the said sections being thus successively lapped over and under each other, the short ends being overlapping and the long ends being underlapping. The said flanges 24 may, however, be omitted.

45 26 is the running board saddle which rests on the ridge cap bends 21, 22 and is recessed on its under side at 27 to receive them and to receive the upper portions of the seam caps. The running boards 28 are secured on top 50 of the saddles 26, and the latter are secured to the ridge pole by the bolts 20 (Figs. 4 and 5).

Each end roof sheet terminates in a depending flange 29 (Fig. 5) which incloses 55 the upper part of the end fascia.

The carlines are formed at one side with a vertical web 30, from which extends a top flange 31 and a bottom flange 32. The top flange extends over the side plates and 60 terminates in depending flanges 33 which are bolted to the outer faces of the side plates. The web 30 is bent out to form securing flanges 34 bolted to the inner faces of the side plates. The top flange is flat- 65 tened for the ridge pole to rest thereon, and

is formed with a hole 35 for the bolt 20 (Fig. 4). The purlins 7 rest on said top flange 31 and are bolted thereto (Fig. 3).

The eaves construction comprises hook strips 36 (Figs. 12, 18) formed with vertical flanges 37 which are nailed or otherwise secured to the side sheathing and are overlaid by the side fascia 9. At the upper edge of the flange 37 the strip is bent inward to form a lower flange 38, and thence upward and outward to form an upper hook-flange 39, the hook-strip being thus of T-form, in cross section. The said hook-flange 39 enters between the roof sheet and its hook-flange 13 and holds the roof sheet mov- 80 ably in place at its eaves edge.

40 is an eaves flashing which incloses the upper part of the side fascia by a depending flange 41 and an inwardly extending body portion, which latter enters between the hook-flange 13 of the roof sheet and the lower flange 38 of the hook-strip, leaving the roof sheet free, and also independent of the hook-strip and removable, by design or accident, without disturbing 90 the connection of said hook-flanges 13, 39.

The outer eaves end of each seam cap 16 is secured and supported by a seam clip 42. Said clip comprises a vertical plate or shank 43 adapted to be secured on the side fascia 95 and formed with bolt and nail holes 44, 45 for that purpose. The shank 43 is at its upper end bent inwardly, nearly horizontally to correspond with the incline of the roof, to form a supporting shoulder 46 100 which rests on the eaves flashing 40. The inner face of the shank is formed with a recess 47 to receive the flashing flange 41. At the inner end of the shoulder 46 the shank is continued upward in the form of a disk 105 48 which serves to close the outer, and otherwise open, end of the seam cap. This disk is connected with the shank 43, around the shoulder 46, by a transverse vertical flange 49, the whole clip being preferably an integral malleable casting. On the inner face 110 of the disk 48 is formed a flange 50 which is circular, or nearly so, which flange nearly encircles the end of the seam cap and takes its weight so that the cap does not rest on, bind or wear the roof sheets. At each side 115 of and partly under the seam cap the clip is formed with extensions 51 and horizontal flanges 52, the former supporting the cap for a considerable distance from its end and the latter overlying and movably confining the roof sheets, the weight of the cap and clip being taken by the shoulder 46 which bears on the flashing at the outer side of and beyond the eaves edge or bend of the roof 125 sheet.

The ends of the ridge seam formed by the roof sheet interlocking flanges and the covering ridge cap sections are inclosed by clips 53 (Figs. 16 and 17), which are preferably 130

malleable castings. Each of these clips comprises a shank portion or plate 54 which is provided with holes 55 for nails or bolts whereby it may be secured to the end fascia 5 (Fig. 5). The shank is formed with a recess 56 on its inner surface to receive the depending flanges 29 of the end roof sheets. At its upper part the clip is formed with a semi-tubular portion or hood 57 which 10 closes the end portion of the said ridge seam, and from this tubular portion are extended inward an extension 58 of the hood, and flat retaining fingers 59 which movably confine the end roof sheets; spaces 60 being 15 left between said parts 58 and 59 for the escape of dirt and moisture and to prevent rusting.

What is claimed is:

1. In a metal car roof, in combination: a car roof frame; roof sheets which are horizontally movable within limits on said frame; seam caps movably uniting the edges of the said roof sheets; and means resting on the top of the car independently of the roof sheets and supporting from below the eaves ends of the said seam caps. 20
2. In a metal car roof, in combination: a car roof frame; roof sheets which are horizontally movable within limits on said frame; seam caps movably uniting the edges of the said roof sheets; means for movably confining the eaves ends of the roof sheets; and seam clips resting on the top of the car independently of the roof sheets and supporting from below the eaves ends of the said seam caps. 30
3. In a metal car roof, in combination: a car roof frame; roof sheets formed at their eaves ends with undeturned hook flanges; seam caps uniting the edges of the said roof sheets; hook strips attached to said frame and engaging within said hook flanges for movably confining the eaves ends of the roof sheets; and means resting on the top 40 of the car independently of the roof sheets and supporting from below the eaves ends of the seam caps. 45
4. In a metal car roof, in combination: a car roof frame; roof sheets which are horizontally movable within limits on said frame; seam caps movably uniting the edges of the said roof sheets; and seam clips resting on the top of the car independently of the roof sheets and supporting from below the eaves ends of the said seam caps. 50
5. In a metal car roof, in combination: a car roof frame; roof sheets which are horizontally movable within limits on said frame; seam caps movably uniting the edges 60 of the said roof sheets; seam clips resting on the top of the car independently of the roof sheets and supporting from below the eaves ends of the said seam caps, and having arms which overlie and movably confine the roof sheets at the sides of the seam. 65
6. In a metal car roof, in combination: a car roof frame; roof sheets resting on said frame, formed with undeturned hook flanges at their eaves ends; seam caps having the side edges of the roof sheets movably interlocked therewith; eaves hook strips having vertical flanges attached to the frame and formed with lower and upper flanges between which are inclosed the hook flanges of the roof sheets; a fascia attached 70 to the frame over the said vertical flanges of the hook strips; eaves flashings inclosing the upper part of the fascia and extending inward between the lower flanges of the hook strips and the hook flanges of the roof sheets; and means resting on said flashings, extending under the eaves ends of the seam caps, and supporting the seam caps independently of the roof sheets and adapted to hold down movably the roof sheets at the 75 sides of the seam caps. 80
7. In a metal car roof, in combination: a car roof frame; roof sheets resting on said frame, formed with upwardly and inwardly turned U-flanges at their sides, with upwardly and outwardly turned U-flanges at their ridge ends and with undeturned hook flanges at their eaves ends; seam caps having the side edges of the roof sheets movably interlocked therewith; eaves hook 90 strips having vertical flanges attached to the frame within the fascia and formed with lower and upper flanges between which are inclosed the hook flanges of the roof sheets; a fascia attached to the frame over the said vertical flanges of the hook strips; eaves flashings inclosing the upper part of the fascia and extending inward between the lower flanges of the hook strips and the hook flanges of the roof sheets; and means resting on said flashings, extending under the eaves ends of the seam caps, and supporting the seam caps independently of the roof sheets and adapted to hold down movably the roof sheets at the 95 sides of the seam caps. 100
8. In a metal car roof, in combination: a car roof frame; roof sheets resting on said frame, formed with upwardly and inwardly turned U-flanges at their sides, with upwardly and outwardly turned U-flanges at their ridge ends and with undeturned hook flanges at their eaves ends; seam caps having the side edges of the roof sheets movably interlocked therewith; eaves hook strips 110 having vertical flanges attached to the frame and formed with lower and upper flanges between which are movably inclosed the hook flanges of the roof sheets; a fascia attached to the frame over the said vertical flanges of the hook strips; eaves flashings inclosing the upper part of the fascia and extending inward between the lower flanges of the hook strips and the hook flanges of the roof sheets; and seam clips resting on 115 120 125 130

said flashings, extending under the eaves ends of the seam caps, and supporting the seam caps independently of the roof sheets and adapted to hold down movably the roof sheets at the sides of the seam caps.

9. In a metal car roof, in combination: a car roof frame; roof sheets resting on said frame, formed with upwardly and inwardly turned U-flanges at their sides, with upwardly and outwardly turned U-flanges at their ridge ends and with undeturned hook flanges at their eaves ends; seam caps having the side edges of the roof sheets movably interlocked therewith; eaves hook strips having vertical flanges attached to the frame and formed with lower and upper flanges between which are movably inclosed the hook flanges of the roof sheets; a fascia attached to the frame over the said vertical flanges of the hook strips; eaves flashings independent of the hook strips, inclosing the upper part of the fascia and extending inward between the lower flanges of the hook strips and the hook flanges of the roof sheets; and seam clips resting on said flashings, extending under the eaves ends of the seam caps, and supporting the seam caps independently of the roof sheets and having arms adapted to hold down movably the roof sheets at the sides of the seam caps.

10. In a metal car roof, in combination: a car roof frame; roof sheets resting on said frame, formed with upwardly and inwardly turned U-flanges at their sides and with undeturned hook flanges at their eaves ends; tubular seam caps having interior upwardly extending flanges with which the side flanges of the roof sheets are movably interlocked; eaves hook strips having vertical flanges attached to the frame within the fascia and formed with lower and upper flanges between which are inclosed the hook

flanges of the roof sheets; a fascia attached to the frame over the said vertical flanges of the hook strips; eaves flashings inclosing the upper part of the fascia and extending inward between the lower flanges of the hook strips and the hook flanges of the roof sheets; and means extending under the eaves ends of the seam caps, and supporting the seam caps independently of the roof sheets and adapted to hold down movably the roof sheets at the sides of the seam caps.

11. A seam clip for supporting from below the seam cap of a car roof, consisting of a vertical shank adapted to be attached to the side of a car, an inward extension at the upper part of said shank which extension is nearly tubular interiorly, and a shoulder arranged between the vertical part of the shank and said extension for supporting the clip and seam cap on the top of the car.

12. In an outside metal car roof, a metal roof-sheet having side flanging and eaves-end flanging adapted to make freely floating connection with their respective retaining means, and having ridge-end flanging adapted to make sliding connection with an opposite roof-sheet, said side-flanging being inwardly rebent over and said eaves-end flanging rebent under the sheet-body, whereby such flanging adapts the sheet to engage freely along both its sides and eaves-end with retaining means supported on and spaced above the sub-structure of the car-roof, substantially as specified.

In testimony whereof, I have hereunto subscribed my name in the presence of two witnesses.

THOMAS NATHAN RUSSELL.
